UNITED STATES PATENT OFFICE.

ERIC R. LUNDIUS, OF RICHMOND HILL, NEW YORK, ASSIGNOR TO WESTERN ELECTRIC COMPANY, INCORPORATED, OF NEW YORK, N. Y., A CORPORATION OF NEW YORK.

PULSING SYSTEM.

Application filed November 1, 1924. Serial No. 747,175.

This invention relates to a telephone exchange system and more particularly to a portable testing system for use in a machine switching system.

5 An automatically operated exchange is made up of apparatus, the majority of which is controlled by the calling or called subscriber for making service connections. Such apparatus is combined into switching units, 10 senders, etc., which include magnetically operated and power driven parts. Each piece of apparatus must be adjusted within certain limits to properly meet service conditions and this adjustment must be maintained throughout 15 the life of the exchange. It is the usual practice to provide testing equipment for the maintenance of apparatus adjustments and where portable test sets are required, means must be provided to make them as self-contained as is possible. This is quite difficult 20 where the parts to be tested are ordinarily controlled by power driven apparatus.

It is the object of this invention to provide an improved pulsing system especially adaptable in units where it is not practical to employ power driven apparatus.

A feature of this invention relates to a pulse generating combination for a portable testing set.

30 Other features of the invention will be apparent from the following description, taken in connection with the accompanying drawings.

While the invention has been disclosed as 35 particularly adapted for testing machine switching apparatus, it will be apparent, however, from the following description that the invention has a wider utility and by slight modification, it could be adapted for testing 40 other types of apparatus.

Fig. 1 illustrates a combined semi-mechanical district switching unit and cord circuit.

Fig. 2 illustrates a semi-mechanical local district selector switch and a sender selector 45 arranged to select senders of a type that control telephone connections to offices having relay call indicator apparatus.

Figs. 3 and 4 illustrate testing equipment for testing the apparatus of the selector units shown in Figs. 1 and 2.

Fig. 5 illustrates the arrangement of Figs. 1 to 4 necessary to show completely the circuits illustrating the invention.

The testing equipment shown in Figs. 3 and 55 4 is mounted in a portable container so that

the tests may be made from a switchboard or certain frames in the apparatus room of a telephone exchange.

Power is transmitted to the apparatus of the testing circuit through jacks which are 60 connected to the power source by patching cords and plugs. Such power connections include current supply for 48 volts direct current, ground and alternating current. The apparatus connections at which symbols 65 for the above are indicated are connected to the terminals of these jacks and the power sources are only connected to the test circuit jacks by the patching cords when the set is in use.

70

*Test of semi-mechanical selector and cord—
Fig. 1.*

75

The test of the apparatus and circuits shown in Fig. 1 is made at a switchboard position which includes plug 190 and jack 193. To initiate the test, the test man inserts plug 190 into jack 314 of the test set and associates patching cord 194 with jacks 193 and 312.

If the apparatus of the testing equipment 80 is in its normal position, a circuit is established to light lamp 333 from grounded battery, through the filament of said lamp, left inner normal contact of relay 357, brush 306 and its associated contact to ground through 85 the lower contact of key 480. When lamp 333 does not light, it indicates to the test man that switch 300 is not in its normal position. He thereupon operates key 345 to energize the switch magnet. This circuit may be 90 traced from grounded battery through the winding and contact of magnet 307, brush 302 and its associated contacts in positions 2 to 13 or 15 to 22, to ground, through the uppermost contact of key 345. The switch brush 95 assembly now rotates under the control of its self-interrupting contact until brush 302 progresses beyond terminal 22. Assuming that lamp 333 has lighted, indicating that the switch is in its normal position, key 346 is now 100 operated to advance the switch from position 1 to position 2. The energizing circuit for the switch magnet 307 may be traced from grounded battery, through the winding of said magnet, contact of key 342, contact of key 346 to ground through the contact of key 105 348. The construction of the switch is such that the stepping pawl, is advanced over a tooth of the stepping ratchet wheel upon the energization of the magnet. Upon the re-

110

lease of key 346, the release of said magnet advances the brush assembly to terminal 2.

In position 2 of switch 300 a circuit is established to light progress lamp 332 from 5 grounded battery, through the filament of said lamp, brush 306 and its associated contact to ground through the lower contact of key 480. A continuity test is now made of the conductors and apparatus associated with 10 the tip and ring contacts of plug 190. This circuit may be traced from grounded battery, through the winding of relay 113, left lower winding of repeating coil 114, lower contact of relay 115, conductor 116, ring conductor of plug 190, ring spring of jack 314, left inner normal contact of relay 358, left outer normal contact of relay 353, brush 305 and its associated contact, winding of relay 350, brush 304 and its associated contact, 15 right outer normal contact of relay 353, right normal contact of relay 358, tip spring of jack 314, tip of plug 190, conductor 117, upper normal contact of relay 115, left upper winding of repeating coil 114 to ground. Relays 113 and 350 are operated in the circuit 20 traced. The operation of relay 350 establishes a circuit to light lamp 320 from ground through the contact of relay 350, filament of lamp 320 to grounded battery. The illumination of lamp 320 indicates to the test man 25 that a continuous circuit is established. The operation of relay 113 is not effective at this time. Upon the illumination of lamp 320 key 346 is again operated and released to 30 advance switch 300 to terminal 3. Magnet 307 is energized and deenergized as previously described.

In position 3 of the switch, progress lamp 331 is lighted from grounded battery, 35 through the lamp filament brush 306 and its associated contact to ground through the lower contact of key 480. A non-operate test of relay 150 is now made by establishing a high resistance circuit through its winding. This may be traced from grounded battery, through the winding of relay 150, conductor 101, sleeve of plug 190, sleeve of jack 314, left outer normal contact of relay 357, resistances 381 and 382 to ground through 40 brush 303 and its associated contact. Relay 150 should not operate when this test is applied. The operation of this relay would indicate that its spring assembly is not in adjustment. This will be shown by the operation of other relays in the district selector which would, in turn, rotate the sequence switch and illuminate lamp 112 in the manner described in Patent No. 1,531,080, issued 45 March 24, 1925 to William L. Dodge. Assuming that relay 150 remains in a non-operated position, key 346 is again operated and released to advance switch 300 to position 4.

In position 4 a circuit is established to light lamp 330 which circuit may be traced in a 50 similar manner to that established for light-

ing lamp 331. A circuit is further established to operate relay 357 from grounded battery through its winding to ground through brush 303 and its associated contact. An operate test of relay 150 is now made by 55 associating the proper value of resistance in circuit with its winding. This circuit may be traced from grounded battery, through the winding of relay 150, conductor 101, sleeve of plug 190, sleeve of jack 314, left outer contact of relay 357, resistance 382 to ground through the right outer contact of relay 357. Resistance 382 is of such value that if relay 150 is in proper adjustment the current through its winding is just enough 60 to actuate its associated armatures. Assuming that relay 150 operates over the circuit traced a circuit is established to operate relay 103 from grounded battery, through the left contacts of key 102, winding of said relay, lower contact of relay 150 to ground, through the right lower contact of cam 104. The operation of relay 103 establishes circuits to operate relays 105, 106 and 107 from 65 grounded battery, through the windings of 90 relays 105 and 106 and through the right winding of relay 107 to ground through the left outer contact of relay 103. The supervisory lamp 108 is lighted from grounded battery, through its filament, right lower contact 95 of cam 109 to ground through the contact of relay 106 to indicate to the test man that relay 106 operated through the contact of relay 103 which must be operated through the contact of relay 150. Lamp 110 is also lighted from grounded battery, through its filament, left lower contact of cam 111 to ground through the right inner contact of relay 105. This is an indication that relay 105 operated 100 in response to the operation of relays 150 and 103. The operation of relay 107 establishes a circuit to energize sequence switch magnet 120 and thus rotates the sequence switch from position 1 to position 2. This circuit may be traced from grounded battery, 105 through the winding of magnet 120, left lower contact of cam 119 to ground through the right contact of relay 107. It will be noted that upon the operation of relay 103 a 110 circuit was established to energize the winding of relay 115, this energizing path, however, is shunted by a ground at cam 104 until the sequence switch rotates out of position 1 1/4. At this time relay 115 operates from this energizing circuit which may be traced 115 from ground through its winding, left inner contact and winding of relay 103 to grounded battery at key 102. It will further be noted that the circuit traced for the operation of relay 115 establishes a locking circuit 120 for relay 103 so that it remains operated after the rotation of the sequence switch out of position 1, and the continued operation of relay 103 maintains relays 105, 106 and 107 in their operated positions. This completes the 125 130

operate test of relay 150 and key 346 is again operated and released to advance the brush members of switch 300 to position 5.

Progress lamp 329 is lighted in this position of the switch over a circuit path similar to that traced for the illumination of previous progress lamps. A monitoring test is now made through the contacts of relay 115 in its operated position. The circuit through contacts of relay 115 is shown schematically as extending through the operator's telephone circuit 195 including receiver 196. For this test alternating current is conducted through a retardation coil bridge, so that a tone is carried through the operator's telephone apparatus to receiver 196. This circuit may be traced from the alternating current source 390, condenser 391, retardation coil 370, brush 305 and its associated contact, left outer normal contact of relay 353, left inner normal contact of relay 358, ring spring of jack 314, ring of plug 190, conductor 116, lower alternate contact of relay 115, apparatus of telephone circuit 195 and receiver 196, upper alternate spring of relay 115, conductor 117, tip of plug 190, tip spring of jack 314, right normal contact of relay 358, right outer normal contact of relay 353, brush 304 and its associated contact, condenser 391 and alternating source 390. The bridge circuit traced allows sufficient alternating current tone to be carried through the circuit apparatus and receiver to be audible to the test man.

The route code and start keys in the switchboard that are required for driving the district circuit (Fig. 1) to the test line are now operated and the district selector sequence switch advances to the selection beyond position No. 10 in the manner described in the aforementioned patent to William L. Dodge. In this position of the district selector sequence switch a circuit is established through the winding of relay 355 over a loop extended through the sender circuit. This circuit may be traced from grounded battery, through the winding of relay 355, right inner normal contact of relay 351, tip spring of jack 312, tip of plug 191, tip conductor of patching cord 194, tip of plug 192, tip spring of jack 193, terminal 149 of the test line, brush 152, right upper and left lower contacts of cam 125, left outer contact of relay 174, thence over a loop circuit through the sender returning through the lower contact of cam 160, brush 153, terminal 151, ring spring of jack 193, ring of plug 192, ring conductor of patching cord 194, ring of plug 191, ring spring of jack 312, left normal contact of relay 351 to ground through brush 303 and its associated contact. Relay 355 operates in the circuit traced and establishes an obvious circuit to operate relay 358. The operation of relay 356 establishes a circuit to operate relay 358 from ground through its right outer contact, winding of relay 358 to grounded battery. The operation of re-

lay 356 further establishes a circuit to energize switch magnet 307, from grounded battery, through the winding of said switch magnet, right inner contact of relay 356 to ground through brush 301 and its associated contact. Magnet 307 is now maintained in an energized position and the brush members are not propelled to the next position until the release of relay 356. The circuit through the sender apparatus as previously described for the operation of relay 355 operates the apparatus in the sender, which operation energizes sequence switch magnet 120 in the district selector switch. This energizing circuit for switch magnet 120 extends from ground in the sender through the right lower contact of cam 119, through the winding of the sequence switch magnet to grounded battery. The district sequence switch now rotates to position 14. The rotation of the sequence switch opens the energizing circuit for relay 356 to cause its release, which in turn opens the energizing circuit for switch magnet 307 to advance the brush members of switch 300 to position 6. A locking circuit is established for relay 358 and it therefore does not release upon the release of relay 356. This locking circuit may be traced from grounded battery, through the winding and left outer contact of relay 358, the left normal contact of relay 359, upper contacts of key 345, sleeve of jack 312, sleeve of plug 191, sleeve conductor of patching cord 194, sleeve of plug 192, sleeve of jack 193, terminal 146, brush 144, brush 155, commutator 154 to ground through the left upper and lower contacts of cam 141. A circuit is now established to operate relay 113, through the contacts of relay 358. This circuit may be traced from grounded battery, through the winding of relay 113, left lower winding of repeating coil 114, lower continuity contacts of relay 115, upper contacts of relay 115, conductor 117, tip of plug 190, tip spring of jack 314, right contact of relay 358, left inner contact of relay 365, retardation coil 370, lower contacts of key 344, left outer normal contact of relay 365, left inner contacts of relay 358, ring spring of jack 314, ring of plug 190, conductor 116, lower contact of relay 115 upper continuity contact of relay 115, left upper winding of repeating coil 114 to ground. Relay 113 operates and lamp 112 is lighted from grounded battery through its filament, contact of relay 113 to ground through the left contact and winding of relay 107. A circuit is established to operate relay 126 in position 14 of the district selector sequence switch from grounded battery through the winding of said relay, right outer contact of relay 105 to ground through the left lower and right upper contact of cam 143.

In position 6 of switch 300 a circuit is established to light progress lamp 328 similar to that previously described for other progress lamps. A further circuit is established

- to operate relay 351 from grounded battery, through its winding to ground through brush 301 and its associated contact. The operation of relay 351 establishes a low resistance circuit for a saturating operate test of polarized relay 163. This circuit may be traced from ground through the left winding of relay 364, brush 305 and its associated contact, left outer normal contact of relay 353, left contact of relay 351, ring spring of jack 312, ring of plug 191, patching cord 194 and plug 192, ring spring of jack 193, terminal 151, brush 153, upper contact of cam 160, lower contact of relay 126, left contact of key 192, lower contact of relay 126, right lower winding of repeating coil 114, lower contact of cam 165, winding of relay 163, upper contact of cam 164, right upper winding of repeating coil 114, upper contact of relay 126, right contact of key 192, upper contact of relay 126, contact of cam 166, brush 152, terminal 149, tip spring of jack 193, tip of plug 192, patching cord 194 and plug 191, tip spring of jack 312, right inner contact of relay 351, right outer normal contact of relay 353, brush 304 and its associated contact, right outer normal contact of relay 454, resistance 470 to grounded battery. Relay 364 operates to establish a circuit from ground through its contact, filament of lamp 320 to grounded battery. The lighting of lamp 320 indicates to the test man that a circuit has been established through relay 163 and that false grounds are not connected to any part of the circuit traced. Relay 163 also operates in the circuit traced, and establishes an operating circuit for relay 136 from grounded battery, through the winding of said relay, right normal contacts of relay 168 to ground through the contact of relay 163. Relay 136 locks over its inner contact to ground at the left contact of cam 104. Key 346 is again operated and released at this time to advance switch 300 to position 7.
- In position 7 of switch 300 progress lamp 327 is lighted over a similar circuit to that traced for previous progress lamps. It will be noted that the operating circuit for relay 163 is opened upon the advance of switch 300 to position 7. Upon the release of relay 163, a circuit is established to operate relay 168 from ground, through the contact of relay 163, right contact of relay 136, right lower and left upper contacts of cam 180, winding of relay 168 to grounded battery. In this position of switch 300, relay 364 is associated in circuit with relay 163 over the tip and ring conductors of the district selector circuit. Therefore, if battery potential is connected to the district apparatus or the tip or ring conductors, relay 364 will operate. Battery should not be connected to said conductors or apparatus at this time. The circuit for this test may be traced from ground through the left winding of relay 364, brush 305 and its associated contact, left outer normal contact of relay 353, left contact of relay 351, ring spring of jack 312, ring of plug 191, patching cord 194, and plug 192, ring spring of jack 193, terminal 351, brush 153, upper contact of cam 160, lower contact of relay 126, left contact of key 192, lower contact of relay 126, right lower winding of repeating coil 114, lower contact of cam 165, winding of relay 163, upper contact of cam 164, right upper winding of repeating coil 114, upper contact of relay 126, right contact of key 192, upper contact of relay 126, lower contact of cam 166, brush 152, terminal 149, tip spring of jack 193, tip of plug 192, patching cord 194, plug 191, tip spring of jack 312, and thence to an open-ended circuit at brush 304. Since no battery is supplied in this circuit relay 364 does not operate, unless faulty potential is associated with the apparatus or conductors of the district selector. If this faulty battery potential should be associated with the apparatus or conductors of the selector circuit, relay 364 operates and establishes a circuit to light lamp 320 as previously traced. This indicates to the test man that trouble is encountered in the selector circuit. Assuming that no trouble is encountered key 346 is operated and released to advance switch 300 to position 8.
- In position 8 of switch 300 a circuit is established to light progress lamp 326 over a circuit similar to that previously traced for other progress lamps. A non-operate test is now applied to relay 163, through resistances of the proper value to allow sufficient current to flow through the circuit established to operate relay 163 if it should be out of adjustment. This circuit may be traced from ground through the left winding of relay 364, brush 304 and its associated contact, right outer normal contact of relay 353, right inner contact of relay 351, tip spring of jack 312 and thence through the winding of relay 163 as previously traced, returning over the ring conductor through the ring spring of jack 312, left contact of relay 351, left outer normal contact of relay 353, brush 305 and its associated contact, resistance 377 to grounded battery. Relay 364 operates in the circuit traced and establishes a circuit to light lamp 320 as previously traced. If relay 163 remains in a non-operated position, lamp 110 in the district selector and cord circuit does not operate. If, however, relay 163 operates when the non-operate test is applied, a circuit is established from ground, through its contact, right contact of relay 168, through the filament of lamp 110 to grounded battery. The illumination of lamp 110 indicates to the test man that relay 163 has operated falsely and is, therefore, not in proper adjustment. Key 346 is operated and released at this time to advance switch 300 to position 9.
- In position 9 of switch 300 a circuit is es-

tablished to light progress lamp 325. A further circuit is established to operate relay 352 from grounded battery, through its winding to ground, through brush 303 and its associated contact. The operation of relay 352 establishes a circuit of the proper resistance value to operate relay 163. This resistance is of such value that a minimum amount of current is allowed to flow through the winding of relay 163 for its operation. This circuit may be traced from grounded battery, through resistance 380, lower contact of key 347, right outer contact of relay 352, left contact of relay 351, ring spring of jack 312, ring of plug 191 and thence through the winding of relay 163 as previously traced, returning over the tip of plug 191, tip spring of jack 312, right inner contact of relay 351 to ground through the right inner contact of relay 352. The operation of relay 163 establishes a circuit to light lamp 110 as previously traced. This indicates to the test man that relay 163 has operated. Key 346 is now operated and released to advance the switch 300 to position 10.

A circuit is established in this position of the switch to light progress lamp 324 from grounded battery, through the lamp filament, left lower contact of key 342, right normal contact of relay 368, brush 306 and its associated contact to ground through the lower contact of key 480. Flashing key 192 is tested in this position. The operation of key 192 establishes an energizing circuit for relay 368. This circuit may be traced from grounded battery through resistance 194, right contact of key 192, upper contact of relay 126, contact of cam 166, brush 152, terminal 149, tip spring of jack 193, tip of plug 192, tip conductor of patching cord 194, tip of plug 191, tip spring of jack 312, right inner contact of relay 351, which has remained in an operated position, right outer normal contact of relay 353, brush 304 and its associated contact, winding of relay 368, brush 305 and its associated contact, left outer normal contact of relay 353, left contact of relay 351, ring spring of jack 312, ring of plug 191, ring conductor of patching cord 194, ring of plug 192, ring spring of jack 193, terminal 151, brush 153, upper contact of cam 160, lower contact of relay 126, left contact of key 192, resistance 193 to ground. Key 192 may now be operated and released a number of times to flash lamp 324. Each operation of key 192 establishes the operating circuit for relay 368, and the release of key 192 opens this circuit to cause the release of said relay. Key 346 is again operated to advance switch 300 to position 11.

The progress lamp 323 corresponding to position 11 of switch 300 is lighted to indicate the position of the switch to the test man. This circuit may be traced from grounded battery through the filament of lamp 323,

brush 306 and its associated contact to ground through the lower contact of key 480. A further circuit is established to operate relay 365 from grounded battery, through its winding to ground through brush 303 and its associated contact. The operation of relay 365 establishes a loop circuit over which relay 113 is operated. This circuit may be traced from grounded battery through the winding of relay 113, left lower winding of repeating coil 114, lower and upper contacts of relay 115, conductor 117, tip of plug 190, tip spring of jack 314, right contact of relay 358, left inner contact of relay 365, upper normal contact of key 344, low resistance 372, left outer contact of relay 365, left inner contact of relay 358, ring spring of jack 314, ring of plug 190, conductor 116, lower and upper contacts of relay 115, left upper winding of repeating coil 114 to ground. The operation of relay 113 establishes a circuit to light lamp 112 as previously traced through the left winding of relay 107. Key 344 is now operated to add other resistances in the testing bridge, which resistances are sufficiently high to cause the release of relay 113. The high resistance bridge circuit may now be traced from grounded battery, through the winding of relay 113 to the tip spring of jack 314 as previously described, thence through the right contact of relay 358, left inner contact of relay 365, resistances 374, 373 and 372, left outer contact of relay 365, left inner contact of relay 358, ring spring of jack 314 and thence to ground through the left upper winding of repeating coil 114. Key 344 may be repeatedly operated and released which should cause relay 113 to operate and release and flash lamp 112. This is an indication to the test man that relay 113 is in proper adjustment.

Since no tests are made in positions 12 and 13 of switch 300, key 346 is operated and released a sufficient number of times to advance the brush assembly to position 14. This completes the test of the cord and district circuits shown in Fig. 1 and the apparatus also shown in Fig. 1 is restored to normal by the removal of the plugs of the testing jacks.

Test of local semi-mechanical district selector—Figure 2.

During the first part of a test of a local semi-mechanical district selector, such as illustrated in Fig. 2, switch 300 remains in position 14 and switch 400 rotates for the application of tests and the operation of test apparatus. It will be noted that the brush members of switch 400 are half the length of those shown on switch 300 and that brush members 401, 402 and 403 are opposite in relation to the switch positions of brush members 404, 405 and 406, so that during the time that brush members 404, 405 and 406 are associated with position terminals, brush mem-

bers 401, 402 and 403 are not thus associated.

To initiate the test of the apparatus and circuits of the selector switch (Fig. 2), plug 228 is inserted in jack 229, plug 226 into jack 227, plug 224 into jack 392 and plug 225 into jack 316. Jacks 229 and 227 are located on a frame in the apparatus room adjacent to the apparatus shown in Fig. 2. The portable box is placed near the jacks so that patching cords 250 and 251 may connect the portable testing box to the frame jacks 229 and 227 and the test man may watch the functioning of the apparatus during the test. Key 342 is now actuated by the test man to establish an operating circuit for relay 353. This circuit may be traced from grounded battery, through resistance 385, winding of relay 353, right upper contact of key 342 to ground through brush 304 and its associated contact. 15 Lamp 478 is lighted to indicate that switch 400 is resting in its normal position. This circuit may be traced from grounded battery through the lamp filament, brush 406 and its associated contact, brush 306 and its associated contact to ground through the lower contact of key 480. Certain ones of the keys in each of the thousands, tens and units key sets are now operated to control the selection of the test line by the district selector (Fig. 20 2). These keys are known as recording keys and are mechanically locked. The contacts 481, 482 and 483 are closed when any one key in each strip is operated. Key 346 is now operated to establish a circuit for start relay 357. This circuit may be traced from grounded battery, through the winding of relay 457, contacts 483, 482 and 481, upper contact of key 346, left inner contact of relay 353 to ground through brush 303 and its associated contact. 25 The operation of relay 457 establishes a locking circuit for itself through its left inner contact to the ground as previously traced for its operating circuit.

The operation of relay 457 further associates relay 458 and resistance 472 with the tip and ring conductors of the district selector (Fig. 2) to start the operation of the district selector circuit. This circuit may be traced from grounded battery through the winding 30 of relay 223, left contacts of cam 211, left outer normal contact of relay 22, left contacts of cam 210, tip spring of jack 229, tip of plug 228, patching cord 250 and plug 224, tip spring of jack 392, left outer contact of relay 353, brush 305 and its associated contact in position 14, left outer contact of relay 457, resistance 472, winding of relay 458, right outer contact of relay 457, brush 304 and its associated contact, right outer contact of relay 353, ring spring 35 of jack 392, ring of plug 224, patching cord 250 and plug 228, ring spring of jack 229, left lower and right upper contacts of cam 215 to ground through the right outer contact of relay 222. Relays 223 and 458 operate in the 40 circuit traced. Resistance 472 in conjunction

with the resistance of relay 458 is of such value that an operating test is made at this time upon relay 223. The operation of relay 458 establishes an operating circuit for relay 460 from grounded battery, through its winding, 70 right outer normal contact of relay 459, contact of relay 458, brush 404 and its associated contact to ground through the right inner normal contact of relay 468. The contacts of relay 460 do not establish effective circuits at 75 this time.

The operation of relay 223 establishes an energizing circuit for relay 221 which may be traced from grounded battery, through the right winding of relay 221, lower contact of cam 218 to ground through the contact of relay 223. The operation of relay 221 establishes an energizing circuit for the sequence switch magnet 200, which may be traced from grounded battery, through its winding, left 80 upper contact of cam 202 to ground through the right contact of relay 221. The sequence switch now rotates from position 1 to position 2. In this position of the sequence switch a circuit is established to operate relay 222 which may be traced from ground through the upper contacts of cam 216, winding of relay 222 to grounded battery, through the winding and contact of the sender selector magnet 220. The resistance of relay 222 85 is of a high value and magnet 220 does not obtain sufficient current to operate. The operation of relay 222 opens the energizing circuit for relay 458 to cause its release. The release of relay 458 removes a shunt from the 90 operating circuit of relay 459. Relay 459 now operates in series with relay 460. This operating circuit may be traced from grounded battery, through said relay windings and right inner contact of relay 460, brush 405 and 95 its associated contact to ground through the right inner contact of relay 468.

The operation of relay 459 establishes an energizing circuit for the magnet 407 associated with switch 400. This circuit may be traced from grounded battery, through the winding of magnet 407 and its associated self-interrupting contact, left contact of relay 459, right outer contact of relay 460, brush 404 and 100 its associated contact to ground through the right inner contact of relay 468. The operation and release of magnet 407 under the control of its self-interrupting contact rotates brushes 404, 405 and 406 into association with the second position terminals. In this position of the switch a circuit is established to energize switch magnet 307 to rotate its brush members from position 14 to position 15. This circuit may be traced from grounded battery, through the winding and associated contact 105 of magnet 307, right inner contacts of relay 459, left inner contacts of relay 353, to ground through brush 303 and its associated contact. Upon the movement of the switches 400 and switch 300, lamp 478 is extinguished and lamp 110 115 120 125 130

477 is lighted in a circuit from grounded battery through its filament brush 306 and its associated contact to ground through the lower contact of key 480. The circuit for relay 457 is opened at brush 303 to cause its release. The release of this relay establishes an energizing circuit for relay 462 from grounded battery, through its winding, right inner normal contact of relay 457, brush 405 and its associated contact to ground through the right inner contact of relay 468.

The operation of relay 462 establishes circuits to send the first pulse to a sender which has been selected by the selector switch shown in Fig. 2. This sender is of the local sender type fully described in the Patent No. 1,531,080, issued March 24, 1925 to William L. Dodge.

Let it be assumed that the test man operates keys 416, 424 and 433 to establish circuit paths for pulses of various character to set the sender apparatus in a manner to direct the selector switch (Fig. 2) to the test line indicated by terminals 236, 237 and 238. The initial pulse is transmitted over a loop extending to the sender of the loop the tip conductor being closed upon the operation of relay 462 from grounded battery through high resistance 471, right inner contact of relay 454, left contact of key 416, left contact of relay 450, left inner contact of relay 462, left inner contact of relay 466, left outer contact of relay 457, brush 305, and its associated contact in position 15, left outer contact of relay 353, tip spring of jack 392, tip of plug 224, patching cord 250 and plug 228, tip spring of jack 229, conductor 252, left lower and upper contacts of cam 210, left outer contact of relay 222, left upper contact of cam 208, brush 225, and thence to the sender register apparatus as described in the previously mentioned patent to William L. Dodge. Simultaneous with the circuit traced over the tip conductor, a ground is associated with the ring conductor which may be traced from the left outer contact of relay 462, left outer contact of relay 466, resistance 473, right outer contact of relay 457, brush 304 and its associated contact, right outer contact of relay 353 ring spring of jack 392, ring of plug 224, patching cord 250 and plug 228, ring spring of jack 229, left lower and right upper contacts of cam 215, right outer contact of relay 222, right upper contact of cam 217, brush 227 and thence to the sender register apparatus as described in the previously mentioned patent to William L. Dodge.

A battery pulse through a high resistance is effective upon the sender register apparatus as a light negative pulse, battery through a low resistance as a heavy negative pulse and ground as a positive pulse.

The operation of relay 462 further establishes a circuit to operate relay 461 from grounded battery, through the winding of

said relay, right contact of relay 462, brush 406 and its associated contact to ground through brush 301 and its associated contact. The operation of relay 461 establishes a circuit to operate relay 467 from grounded battery through its winding to ground through the right contact of relay 461. The operation of relay 461 further establishes a circuit to energize switch magnet 407 which may be traced from grounded battery, through the winding and associated contact of magnet 407, left contact of relay 461, brush 404 and its associated contact to ground through the right inner contact of relay 468. It should be noted that relay 461 is a slow operating relay in order to allow sufficient time for the first pulse to be transmitted to the sender before switch 400 advances from position 2 to position 3, and further that relay 467 is slow to release in order to allow further time for pulsing before establishing circuits to energize the next pulse relay 463. The rotation of switch 400 from position 2 to position 3 opens the energizing circuit for relays 461 and 462 to cause their release. The release of relay 461 opens the energizing circuit of relay 467. The release of relay 467 establishes a circuit to rotate the switch from position 3 to position 4. This circuit may be traced from grounded battery through the winding of magnet 407 and contact associated therewith, right contact of relay 467, brush 404 and its associated contact to ground through the right inner contact of relay 468.

A circuit is established for relay 463 in position 4 of switch 400 which may be traced from grounded battery, through the winding of said relay, brush 405, and its associated contact to ground through the right hand contact of relay 468. The operation of relay 463 establishes a pulse circuit over the tip and ring conductors which may be traced from ground, through the left outer contact of relay 463, left outer contact of relay 457, brush 305 and its associated contact, left outer contact of relay 353, tip spring of jack 392, and thence over the tip conductor of the selector switch (Fig. 2) to the register apparatus of the sender as previously traced upon the operation of relay 462. Grounded battery is associated with the ring conductor through high resistance 474, left inner contact of relay 463, resistance 473, outer right back contact of relay 457, brush 304 and its associated contact, right outer contact of relay 353, ring spring of jack 392 and thence over the ring conductor of the selector switch (Fig. 2), to the sender register apparatus as previously traced. The operation of relay 463 further establishes a circuit to operate relay 461 from grounded battery, through its winding, right normal contact of relay 462, right contact of relay 463, brush 406 and its associated contact to ground through brush 301 and its associated contact. As previous-

- ly described the operation of relay 461 operates relay 467 and rotates switch 400 one position from 4 to 5 and upon the rotation of the switch, relays 461, 463 and 467 are released.
- 5 The release of relay 467 advances switch 400 one position from 5 to 6 in the manner previously described. In this position of the switch a circuit is established to energize relay 464 from grounded battery, through its winding, brush 405 and its associated contact to ground through the right inner contact of relay 468. Since the test man actuated key 416, the tip conductor is open and therefore no potential is transmitted over this conductor to the sender register apparatus through the contacts of relay 464. Ground is connected to the ring conductor over a circuit which may be traced through the left outer contact of relay 464, left outer contact of relay 466, resistance 473, brush 304 and its associated contact, right outer contact of relay 353, ring spring of jack 392 and thence over the ring conductor of the selector switch (Fig. 2) to the sender register apparatus.
- 20 25 This is without effect since the tip conductor is open. The relay 461 is operated through the right contact of relay 464 in the same manner as described through the contacts of relays 463 and 462. Switch 400 is advanced to position 7 through the contact of relay 461 and to position 8 through the contact of relay 467 upon its release.
- An energizing circuit for relay 465 is established in position 8 of switch 400 from 35 grounded battery, through the winding of said relay, brush 405 and its associated contact to ground through the right inner contact of relay 468. A ground is now connected to the tip conductor, and battery through a low resistance is connected to the ring conductor of the loop extending to the sender register apparatus for transmitting a heavy negative pulse. The tip circuit may be traced from ground through the left outer contact of relay 465, left outer contact of relay 457, brush 305 and its associated contact, left outer contact of relay 353, tip spring of jack 392 and thence over the tip conductor of the selector switch (Fig. 2) to the sender register apparatus. The ring conductor circuit 40 may be traced through the winding of low resistance 470, right outer contact of relay 454, right contact of key 416, right outer contact of relay 451, left inner contact of relay 465, resistance 473, right outer contact of relay 457, brush 304 and its associated contact, right outer contact of relay 353, ring spring of jack 312, and thence over the ring conductor of the selector switch (Fig. 2) to the sender register apparatus. The operation of relay 465 further establishes an energizing circuit for relay 461 which in turn establishes an energizing circuit for relay 467 in the manner previously described. The switch 400 progresses from position 8 to position 9

under the control of the circuit established through the contact of relay 461 and from position 9 to position 10 over the circuit established through the normal contact of relay 467 upon its release. In this position a circuit is established to operate relays 450 and 451 from grounded battery in series through their windings brush 405 and its associated contact to ground through the right inner contact of relay 468. The operation of relays 450 and 451 transfers the pulse control leads from the thousands keys 410 to 419 inclusive to the tens keys 420 to 429 inclusive.

The operation of relay 451 further establishes a circuit to rotate switch 400 from position 10 to position 12. This circuit may be traced from grounded battery, through the winding and associated contact of switch magnet 407, right inner contact of relay 451, brush 404 and its associated contacts in positions 10 and 11 to ground through the right inner contact of relay 468.

A circuit is again established for relay 462 in position 12 from grounded battery, through its winding, right inner contact of relay 457, brush 405 and its associated contact to ground; through the right inner contact of relay 468. The first tens pulse is transmitted to the sender through the contacts of this relay.

It will be remembered that tens key 424 is the one operated by the test man. The tip conductor is opened at key 424 and thus no potential is impressed over this conductor through the contacts of relay 462. A ground is connected to the ring conductor through the left outer contact of relay 462, left outer contact of relay 466, resistance 473, brush 304 and its associated contact, outer contact of relay 353, ring conductor of jack 392 and thence over the ring conductor of the selector to the register apparatus of the sender but is without effect since the sender loop is open at the tip conductor. The operation of relay 462 further establishes an operating circuit for relay 461 and the operation of relay 461 establishes an energizing circuit for relay 467. Switch 400 is now advanced into position 14 in the manner previously described for the advance of this switch.

Relay 462 is released and an energizing circuit is established for relay 463 in position 14 of the switch from grounded battery, through its winding, brush 405 and its associated contact to ground through the right inner contact of relay 468. The operation of relay 463 connects ground with the tip conductor over a circuit traced through the left outer contact of relay 463, left outer contact of relay 457 brush 305 and its associated contact, left outer contact of relay 353, tip conductor of jack 392 and thence over the tip conductor of the selector, Fig. 2, to the sender register apparatus. Battery is connected through a high resistance with the ring con-

- ductor over a circuit which may be traced from grounded battery, through resistance 474, left inner contact of relay 463, resistance 473, brush 304 and its associated contact, 5 right outer contact of relay 353, ring conductor of jack 392 and thence to the sender register apparatus as previously traced. The resulting impulse over the sender loop is weak and of negative polarity. The operation 10 of relay 463 further establishes an energizing circuit for relay 461 and in turn for relay 467 to rotate the switch 400 into position 16 as previously described.
- Relay 463 is released and an energizing circuit is established for relay 464 from grounded battery, through its winding, brush 15 405 and its associated contact to ground through the right inner contact of relay 468. The operation of relay 464 associates battery through a high resistance with the tip conductor over a circuit which may be traced from grounded battery, through resistance 471, right inner contact of relay 454, left contact of key 424, left outer contact of relay 20 453, left contact of relay 451, left inner contact of relay 464, left inner contact of relay 466, left outer contact of relay 457, brush 305 and its associated contact, left outer contact of relay 353 tip conductor of jack 392 and thence to the sender register apparatus as 25 previously traced. Ground is associated with the ring conductor through the left outer contact of relay 464, left outer contact of relay 466, resistance 473, right outer contact of relay 457, brush 304 and its associated contact, right outer contact of relay 353, ring spring of jack 392 and thence to the sender register apparatus as previously described. The resulting impulse over the sender loop 30 is positive. The operation of relay 464 further establishes an energizing circuit for relay 461 and the operation of relay 461 establishes an energizing circuit for relay 467. Switch 400 is now rotated to position 18 in the manner previously described.
- Relay 464 is released and an energizing circuit for relay 465 is established from grounded battery through its winding, brush 405 and its associated contact to ground 35 through the right inner contact of relay 468. The operation of relay 465 associates a ground potential with the tip conductor through the left outer contact of relay 465, left outer contact of relay 457, brush 304 and its associated contact, left outer contact of relay 353, tip spring of jack 392 and thence to the sender register apparatus as previously described. Battery potential is associated through a high resistance 475 with the ring conductor through the left inner contact of relay 465, resistance 473, right outer contact of relay 457, brush 304 and its associated contact, right outer contact of relay 353, ring spring of jack 392 and thence to the sender register apparatus as previously described. The resulting impulse is weak and of negative potential. The operation of relay 465 further establishes a circuit to energize relay 461 and the operation of relay 461 establishes an energizing circuit for relay 467. Switch 400 is now rotated from position 18 to position 20 in the manner previously described for the rotation of this switch.
- Relay 465 is released when switch 400 rotates from position 18 to position 19 and an energizing circuit for relays 452 and 453 is established in position 20, from grounded battery in series through the windings of said relays, brush 405 and its associated contact to ground through the right inner contact of relay 468. The operation of relays 452 and 453 transfers the pulse relays from the tens key set to the units key set. The operation of relay 453 further establishes a circuit to rotate switch brushes 401, 402 and 403 to terminal 1. This circuit may be traced from grounded battery, through the winding and associated contact of magnet 407, right inner contact of relay 453, brush 404 and its associated contacts in positions 20, 21 and 22 to ground through the right front contact of relay 468.
- Switch brushes 401, 402 and 403 are now associated with the terminals of position No. 1 and brushes 404, 405 and 406 are open. A circuit is now established to rotate switch 400 from position 1 to position 2 where the pulsing apparatus is again associated with the tip and ring conductors extending to the sender. The circuit for rotating switch 400 may be traced from grounded battery, through the winding and associated contact of magnet 407, right normal contact of relay 467, brush 401 and its associated contact to ground through brush 301 and its associated contact.
- An energizing circuit for relay 462 is established in position 2 of switch 400. This circuit may be traced from grounded battery, through the winding of relay 462, right inner contact of relay 457, brush 402 and its associated contact, to ground through the right inner contact of relay 468. Battery is now connected through high resistance 471 with the tip conductor through the right inner contact of relay 454, left contact of key 433, left contact of relay 452, left contact of relay 450, left inner contact of relay 462, left inner contact of relay 466, left outer contact of relay 457, brush 305 and its associated contact, left outer contact of relay 353, tip spring of jack 392 and thence to the sender register apparatus as previously traced. A ground is associated with the ring conductor through the left outer contact of relay 462, left outer contact of relay 466, resistance 473, right outer contact of relay 457, brush 304 and its associated contact, right outer contact of relay 353, ring spring of jack 392 thence to the sender register apparatus. The resulting

pulse of current over the sender loop is of positive polarity. The operation of relay 462 further establishes an energizing circuit for relay 461 which may be traced from ground-
5 ed battery, through its winding, right contact of relay 462, brush 403 and its associated contact to ground through brush 301 and its as-
sociated contact. The operation of relay 461 establishes an energizing circuit for relay 467
10 and an energizing circuit for switch magnet 407 to rotate the switch from position 2 to
position 3. The energizing circuit for mag-
net 407 may be traced from grounded battery,
15 through its winding and associated contact,
left contact of relay 461, brush 401 and its
associated contact to ground through brush
301 and its associated contact. Upon the ro-
tation of switch 400 from position 2 to posi-
20 tion 3 the energizing circuit for relay 461 is
opened to cause its release, thus opening the
energizing circuit for relay 467 which slowly
releases. The rotation of switch 400 from
position 2 to position 3 further opens the
25 energizing circuit for relay 462 to cause its
release. The release of relay 467 establishes
an energizing circuit for switch magnet 407
to rotate the switch from position 3 to posi-
tion 4. This energizing circuit may be traced
30 from grounded battery, through the winding
and associated contact of magnet 407, right
normal contact of relay 467, brush 401 and its
associated contact to ground through the
brush 301 and its associated contact.
35 A circuit is now established to operate
relay 463 from grounded battery, through
its winding, brush 402 and its associated con-
tact to ground through the inner right con-
tact of relay 468. The operation of relay 463
40 associates ground potential with the tip con-
ductor through the left outer contact of relay
463, left outer contact of relay 457, brush 305
and its associated contact, right outer contact
of relay 353, tip spring of jack 392 and thence
45 to the sender register apparatus as previously
described. Battery potential through low
resistance 470 is associated with the ring con-
ductor through the right outer normal con-
tact of relay 454, right contact of key 433,
50 right outer contact of relay 452, right outer
contact of relay 450, left inner contact of
relay 463, resistance 473, right outer contact
of relay 457, brush 304 and its associated
contact, right outer contact of relay 353, ring
55 spring of jack 392 and thence to the sender
register apparatus as previously described.
An impulse of heavy negative potential is
thus transmitted over the loop extending to
the sender. The operation of relay 463 fur-
60 ther establishes an energizing circuit for re-
lay 461 and the operation of relay 461 estab-
lishes an energizing circuit for relay 467.
The operation of relay 461 further establishes
an energizing circuit for magnet 407 to ro-
65 late the switch 400 from position 4 to posi-
tion 5 in the manner previously described.

In position 5 the energizing circuit for relays
461 and 463 is opened to cause their release.
The release of relay 461 opens the energizing
circuit for relay 467 to cause its release which
establishes an energizing circuit for magnet 70
407 to rotate switch 400 from position 5 to
position 6.

In this position of the switch a circuit is
established to operate relay 464 from ground-
ed battery, through its winding, brush 402
75 and its associated contact to ground through
the right inner contact of relay 468. The op-
eration of relay 464 does not close the tip con-
ductor, but associates a ground potential with
the ring conductor through the left outer
80 contact of relay 464, left outer normal con-
tact of relay 466, resistance 473, right under
contact of relay 457, brush 304 and its asso-
ciated contact, right outer contact of relay
353, ring spring of jack 392 and thence to the
85 sender register apparatus as previously de-
scribed. Since the tip conductor is open no
impulse is sent over the loop to the sender.
The operation of relay 464 establishes an en-
90 ergizing circuit for relay 461 and the oper-
ation of relay 461 establishes an energizing
circuit for relay 467 to rotate switch 400
from position 6 to position 8 in the manner
previously described. Relay 464 is released
95 upon the rotation of the switch and an en-
er99 ergizing circuit is established for relay 465
when the switch brush 402 arrives in posi-
tion 8.

Ground is now associated with the tip con-
100 ductor through the left outer contact of re-
lay 465, left outer normal contact of relay
457, brush 305 and its associated contact, left
outer contact of relay 353, tip spring of jack
392 and thence to the sender register appara-
105 tus. Battery through high resistance 475 is
associated with the ring conductor through
the left inner contact of relay 465, resistance
473, right outer contact of relay 457, brush
304 and its associated contact, right outer
110 contact of relay 353, ring spring of jack 392
to the sender register apparatus. The re-
sultant impulse is therefore weak and of neg-
ative potential. The operation of relay 465
further establishes an energizing circuit for
115 relay 461 and the operation of relay 461 estab-
lishes an energizing circuit for relay 467 for
the advancement of switch 400 from position
8 to position 10.

An energizing circuit is established in po-
120 sition 10 of switch 400 for relays 454 and 466
from grounded battery, through their wind-
ings in series, brush 402 and its associated
contact to ground through the right inner
contact of relay 468. The operation of re-
125 lays 454 and 466 arranges the pulsing circuit
in such a manner that a series of pulses
may be transmitted to the sender which
represent zero pulses. Sufficient pulses have
already been transmitted to the sender to
130 position the code registers for directing

the selector switch, Fig. 2, to the test line. It is, however, necessary to transmit a series of ten light negative pulses to the sender in order to satisfy the sender numerical and station registers. The light negative pulses in the order transmitted are known as zero pulses.

The operation of relay 466 establishes a circuit to advance switch 400 from position 10 to position 12 from grounded battery, through the winding and associated contact of switch magnet 407, right outer contact of relay 466, brush 401 and its associated contacts in positions 10 and 11 to ground through brush 301 and its associated contact in position 15. An energizing circuit is established for relay 462 in position 12 of switch 400 from grounded battery, through the winding of said relay, right inner contact of relay 457, brush 402 and its associated contact to ground through the right inner contact of relay 468. Ground potential is now associated with the tip conductor through the left outer contact of relay 462, left inner contact of relay 466, left outer contact of relay 457 and thence to the tip conductor of the selector switch, Fig. 2, and the sender register as previously traced. Battery potential is associated with the ring conductor through high resistance 471, right inner contact of relay 454, left inner contact of relay 462, left outer contact of relay 466, resistance 473, right outer contact of relay 457 and thence to the ring conductor of the selector switch, Fig. 2, and sender register apparatus as previously described. This represents the first of a series of zero pulses transmitted to the sender. The operation of relay 462 further establishes an energizing circuit for relay 461 which in turn establishes an energizing circuit for relay 467 in the manner previously described to rotate switch 400 from position 12 to position 14. Relay 462 is released and an energizing circuit is established for relay 463 in the manner previously described. The operation of relay 463 associates ground potential with the tip conductor through its left outer contact, the left outer contact of relay 457 to the tip conductor of selector switch, Fig. 2, and sender register as previously described. Battery is associated with the ring conductor through high resistance 474, left inner contact of relay 463, resistance 473, right outer contact of relay 457 to the ring conductor of the selector, Fig. 2, and sender register as previously described. A second impulse of light negative potential is therefore transmitted over the sender loop circuit. The operation of relay 463 further establishes energizing circuits for relays 461 and 467 as previously described to advance the switch 400 from position 14 to position 16. Relay 463 is released and an operating circuit is established for relay 464. The operation of relay 464 again associates ground potential with the tip conductor

through its left outer contact, left inner contact of relay 466, left outer contact of relay 457 to the tip conductor of the selector, Fig. 2, and sender registers. Battery potential is associated with the ring conductor through high resistance 471, left outer contact of relay 454, left inner contact of relay 464, left outer contact of relay 466, resistance 473, right outer contact of relay 457 and thence to the ring conductor of the selector, Fig. 2, and sender register apparatus, resulting in the transmission of a third impulse of light negative potential. The operation of relay 464 further establishes a circuit to operate relay 461 which in turn establishes a circuit to operate relay 467 which combination advances switch 400 from position 16 to position 18. Relay 464 is released upon the rotation of switch 400 out of position 16 and a circuit for relay 465 is established in position 18. The operation of relay 465 again associates ground potential with the tip conductor through its left outer contact and the left outer contact of relay 457. Battery potential through high resistance 475 is associated with the ring conductor through the left inner contact of relay 465, resistance 473, right outer contact of relay 457 and thence to the sender register apparatus as previously described. This results in the transmission of a fourth impulse of light negative potential. The operation of relay 465 further establishes an energizing circuit for relay 461, the operation of which establishes a circuit for relay 467 to advance switch 400 from terminal 18 to terminal 20 in the manner previously described. Upon reaching terminal 20 a further circuit is established to energize switch magnet 407 to rotate the switch to position 1. This circuit may be traced from grounded battery, through the winding and associated contact of magnet 407, brush 401 and its associated contacts in positions 20, 21 and 22 to ground through brush 301 and its associated contact.

It will be noted that when brushes 401, 402 and 403 have rotated beyond terminal 22, brushes 404, 405 and 406 are resting upon terminal 1 and therefore circuits are established through these brushes for further operation of the pulse relays to complete the zero pulses to be transmitted to the sender register apparatus. Four zero pulses have been transmitted out of a total ten which are required to satisfy the sender. Switch 400 is advanced from position 1 to position 2 since a circuit is established to energize magnet 407 upon its arrival in position 1. This may be traced from grounded battery through the winding and associated contact of magnet 407, left contact of relay 459, right outer contact of relay 460, brush 404 and its associated contact to ground through the right inner contact of relay 468.

An energizing circuit for relay 462 is established in position 2 of switch 400 from

grounded battery through its winding, right inner contact of relay 457, brush 405 and its associated contact to ground, through the right inner contact of relay 468. The operation of relay 462 associates a ground with the tip conductor and battery with the ring conductor through high resistance 471 for transmitting a zero pulse to the sender apparatus. Switch 400 is rotated to position 4 by the operation of relays 461 and 467. Relay 462 is released and relay 463 operated in the manner previously described. A ground is now associated with the tip and battery through a high resistance 474 associated with the ring the same as previously described and the switch 400 is rotated to position 6. In position 6, relay 464 is operated to transmit the seventh pulse and in position 8, relay 465 is operated to transmit the eighth zero pulse to the sender register apparatus. The operation of relay 465 causes switch 400 to rotate from position 8 to position 10 by operating relays 461 and 467. In position 10, a circuit is immediately established to rotate switch 400 to position 12 by the energization of magnet 407 from grounded battery through its winding and associated contact, right inner contact of relay 451, brush 404 and its associated contact to ground through the right inner contact of relay 468. In position 12, a circuit is established to operate relay 462 to transmit the ninth zero pulse to the sender register apparatus and to rotate the switch into position 14. In position 14, relay 463 is operated to transmit the tenth zero pulse to the sender register apparatus. The operation of relay 463 again operates relay 461 to rotate switch 400 into position 15 as previously described. A circuit is now established to operate relay 468 from grounded battery through resistance 479, winding of relay 468, right inner contact of relay 466, brush 406 and its associated contact to ground through brush 301 and its associated contact. Relay 468 locks through its left contact and establishes a circuit through its right inner contact to energize switch magnet 407. The switch now rotates, under the control of its self-interrupting contact, one complete revolution and until brush 403 is associated with the contact in position 19 where a shunt circuit is established to release relay 468. This shunt circuit may be traced from a point between resistance 479 and the winding of relay 468 through brush 403 and its associated contact to ground through brush 301 and its associated contact. The operation of relay 468 further opens the locking circuit for relays 450, 451, 452 and 453 to cause their release. Upon the release of relay 468, magnet 407 releases and switch 400 progresses to position No. 20. In positions 20, 21 and 22, a circuit is established to energize switch magnet 407 in order that switch 400 may be rotated to normal. This circuit may be traced from grounded battery through the winding and associated contact of magnet 407, brush 401 and its associated contacts in position 20, 21 and 22 to ground through brush 301 and its associated contact. During the operation of relay 468, a circuit was established to rotate switch 300 from position 15 to position 16. This circuit may be traced from grounded battery through the winding and associated contact of magnet 307, right outer contact of relay 468 to ground through brush 303 and its associated contact in position 15. Lamp 477 is extinguished upon the advance of switch 300. Upon the completion of pulses transmitted from the testing circuit to the sender register apparatus, the selector switch (Fig. 2) is brought under the control of said sender and the selector sequence switch rotates into position 4. A circuit is thus established to energize relay 368. This may be traced from grounded battery through the winding of relay 223, right contacts of cam 210, conductor 253, ring contact of jack 229, ring of plug 228, patching cord 250, plug 224, ring of jack 392, right outer contact of relay 353, brush 304 and its associated contact, winding of relay 368, brush 305 and its associated contact, left outer contact of relay 353, tip spring of jack 392, tip of plug 254, patching cord 250 and plug 228, tip spring of jack 229, conductor 252 to ground through the right contacts of cam 211. Relays 223 and 268 operate in the circuit traced. The operation of relay 223 energizes relay 222 to establish circuits for the advancement of the selector sequence switch as described in the patent to William L. Dodge hereinbefore mentioned. The operation of relay 368 establishes a circuit to operate relay 360 from grounded battery through the winding of said relay, right normal contact of relay 367, left lower contact of key 342, contact of relay 368 to ground through the left upper contact of key 342. The operation of relay 360 extinguishes lamp 338 and lights lamp 339 from grounded battery through its filament, right outer contact of relay 360, brush 306 and its associated contact to ground through the lower contact of key 480. The operation of relay 360 further establishes a circuit to energize switch magnet 307 from grounded battery through its winding, left inner contact of relay 360 to ground through brush 303 and its associated contact. The selector sequence switch continues to rotate under the control of the circuit established and upon rotating out of position 4, the circuit for relay 368 is opened to cause its release. The release of relay 368 opens the energizing circuit for relay 360 to cause its release and the release of relay 360 opens the energizing circuit for magnet 307 to propel the brush assembly from position 16 to position 17. Lamp 341 is now lighted to indicate to the test man that the selector se-

quence switch has progressed beyond position 4. This circuit may be traced from grounded battery through the lamp filament, right inner contact of relay 360, left outer normal contact of relay 367, brush 306 and its associated contact to ground through the lower contact of key 480.

When the district selector sequence switch has rotated to position 5, a circuit is again established to operate relay 368 which circuit is the same as previously traced for its operation with the exception that grounded battery through the winding of relay 223 is carried to the left upper and right lower contacts of cam 211 and thence over the tip conductor instead of over the ring conductor as previously traced. Also, ground is associated with the ring conductor through the left contacts of cam 215 and left upper contact of cam 216. The operation of relay 368 establishes the circuit previously traced to operate relay 360. Lamp 341 is extinguished and lamp 340 is lighted from grounded battery through its filament, contact of relay 360, left outer normal contact of relay 367, brush 306 and its associated contact in position 17 to ground through the lower contact of key 480. Upon further movement of the district selector sequence switch (Fig. 2) the energizing circuit for relay 368 is opened to cause its release. Relay 360, however, does not release since an energizing circuit through the winding of relay 367 establishes a locking circuit for relay 360. The release of relay 368 removes a shunt path from the winding of relay 367. This shunt path may be traced to the ground established by the operation of relay 360. The energizing circuit for relay 367 may be traced from grounded battery through the windings of relays 360 and 367, left outer contact of relay 360 to ground through brush 303 and its associated contact. The district selector (Fig. 2) is now further controlled by the sender to select the test line indicated by terminals 236, 237 and 238.

After the selection of the test line, the district selector sequence switch moves into position 12 for selections beyond. Since there are no further selections to be made, the selector sequence switch magnet is energized by the sender to rotate the sequence switch to position 13. In this position of the selector sequence switch a bridge circuit is associated with the tip and ring conductors of the test line to energize relay 361 of the testing circuit. This circuit may be traced from grounded battery through resistance 378, winding of relay 361, right normal contact of relay 362, tip spring of jack 316, tip of plug 225, patching cord 251 and plug 226, tip spring of jack 227, terminal 238, brush 235, right lower contact of cam 208, outer left contact of relay 222, left upper contact of cam 213, brush 234, terminal 237, ring spring of jack 227, ring of plug 226, patching cord 251 and plug 225, ring spring of jack 316 to ground through the uppermost contact of key 344. If the continuity circuit is established as traced, relay 363 remains locked and relay 368 operates. The operation of relay 368 establishes a circuit to light lamp 337, and to operate relay 456 from grounded battery through the winding of relay 456, filament of lamp 337, right contact of relay 367, left lower contact of key 342, contact of relay 368 to ground through the left upper contact of key 342. The operation of relay 456 is not effective at this time. The lighting of lamp 337 and lamp 335 indicates to the test man that the

cord 251 and plug 225, ring spring of jack 316, to ground through the uppermost contact of key 344. The operation of relay 361 establishes an obvious energizing circuit for relay 363, relay 363 locking over the circuit previously traced to the selector of Fig. 2. The operation of relay 363 establishes an obvious energizing circuit for relay 362. The operation of relay 362 opens the energizing circuit for relay 361 to cause its release. The operation of relay 362 further establishes a circuit to light lamp 334 as an indication to the test man that the district selector (Fig. 2) is properly functioning. The lamp circuit may be traced from grounded battery through resistance 379, filament of lamp 334, left contact of relay 362, lower contact of key 348, left outer contact of relay 367, brush 306 and its associated contact, to ground through the lower contact of key 480. The district selector sequence switch continues to rotate through positions 13, 14 and 15 and upon its rotation beyond position 15½ the bridge holding circuit for relay 363 is opened and a locking circuit is substituted in the form of a continuity test of the talking conductors and apparatus associated therewith in the selector switch circuit Fig. 2. In position 16 of the district selector sequence switch a circuit is established from the testing circuit to the test line over the tip and ring conductors of the district selector (Fig. 2) and thence over conductors 252 and 253 again to the testing circuit. This may be traced from grounded battery through the winding and right contact of relay 363, tip spring of jack 316, tip of plug 225, patching cord 251, plug 226, tip spring of jack 227, tip terminal 238, brush 235, left upper contact of cam 214, conductor 252, tip spring of jack 229, tip of plug 228, patching cord 250 and plug 224, tip spring of jack 392, left outer contact of relay 353, brush 305 and its associated contact, winding of relay 368, brush 304 and its associated contacts, right outer contact of relay 353, ring spring of jack 392, ring of plug 224, patching cord 250 and plug 228, ring spring of jack 229, conductor 253, right upper contact of cam 213, brush 234, terminal 237, ring spring of jack 227, ring of plug 226, patching cord 251 and plug 225, ring spring of jack 316 to ground through the uppermost contact of key 344. If the continuity circuit is established as traced, relay 363 remains locked and relay 368 operates. The operation of relay 368 establishes a circuit to light lamp 337, and to operate relay 456 from grounded battery through the winding of relay 456, filament of lamp 337, right contact of relay 367, left lower contact of key 342, contact of relay 368 to ground through the left upper contact of key 342. The operation of relay 456 is not effective at this time. The lighting of lamp 337 and lamp 335 indicates to the test man that the

district selector has rotated its sequence switch into talking position that it has properly responded to the setting of the sender registers in response to the pulses transmitted thereto.

- 5 The test of the local district selector circuit is now completed and key 345 is operated to rotate switch 300 to normal over a circuit which may be traced from grounded battery 10 through the winding and associated contact of switch magnet 307, brush 302 and its associated contacts to ground through the uppermost contact of key 345. When switch 300 has been restored to normal a circuit is 15 established to light lamp 333 from grounded battery through the lamp filament, left inner normal contact of relay 357, brush 306 and its associated contact to ground through the lower contact of key 480. The operation 20 of key 345 further opens the holding circuits for relays which are in an operated position at the time that the test is completed.

What is claimed is:

1. In a telephone exchange system, means 25 for transmitting trains of impulses of various characteristics, said means comprising keys operable to vary the character of impulses in each train, relays progressively operable to establish circuit paths for the transmission 30 of the individual impulses of each train and a step-by-step switch to control the progressive operation of said relays.

2. In a telephone exchange system, means 35 for transmitting trains of impulses, said impulses varying in polarity and strength, said means comprising keys operable to vary the character of individual impulses of said train, relays progressively operable to establish circuit paths for the transmission of the 40 individual impulses of each train and a step-by-step switch to control the progressive operation of said relays.

3. In a telephone exchange system, means 45 for transmitting trains of impulses of various characteristics, said means comprising keys operable to vary the character of impulses in each train, relays progressively operable to establish circuit paths for the transmission of the individual impulses of each train, a 50 step-by-step switch to control the progressive operation of said relays and means under the control of said relays to advance said switch.

4. In a telephone exchange system, a device 55 for transmitting trains of impulses of various characteristics, comprising a switch having stationary contacts and a movable brush, said brush being progressively positioned under the control of the electrical condition on successive contacts for transmitting a train of

impulses of various characteristics, and means for varying the characteristic of the impulse transmitted in any given position of said switch.

5. In a telephone exchange system, a device 65 for transmitting trains of impulses of various characteristics, comprising a switch having stationary contacts and a movable brush, said brush being progressively positioned under the control of the electrical condition 70 on successive contacts for varying the characteristic of successive impulses in each train, and means for varying the polarity and strength of impulses transmitted in any given position of said switch. 75

6. In a telephone exchange system, a device 80 for transmitting trains of impulses of various characteristics, comprising a switch having stationary contacts and a movable brush, said brush being progressively positioned under the control of the electrical condition on successive contacts for varying the characteristic of the successive impulses in a train, means for controlling the characteristic of the impulse transmitted in any given position of 85 said switch, and means operable in response to the electrical condition of said switch contacts for transmitting the impulses of said trains.

7. In a telephone exchange system, a device 90 for transmitting trains of impulses of various characteristics, comprising a switch having stationary contacts and a movable brush, said brush being progressively positioned under the control of the electrical condition 95 on successive contacts for varying the characteristic of successive impulses in a train, means for varying the characteristic of the impulse transmitted in any given position of said switch, and relays variably operable in response to the electrical condition of said switch contacts for transmitting the impulses of 100 said trains.

8. In a telephone exchange system, a device 105 for transmitting trains of impulses of various characteristics, comprising a switch having stationary contacts and a movable brush, said brush being progressively positioned under the control of the electrical condition 110 on successive contacts for varying the characteristic of successive impulses in a train, keys for varying the characteristic of the impulse transmitted in any given position of said switch, and relays variably operable in response to the electrical condition 115 on said switch contacts for transmitting the impulses of said trains.

In witness whereof, I hereunto subscribe my name this 23d day of October, A. D. 1924.

ERIC R. LUNDIUS.
